VALVE SEAT RECONDITIONING TOOL

Francis G. Livingston and Oren B. Harms,
Algona, Iowa, assignors to Livingston Tool Co.,
Algona, Iowa, a partnership

Application March 24, 1950, Serial No. 151,666

1 Claim. (Cl. 51—197)

1

This invention relates to valve seat reconditioning tools.

Most valve seat reconditioning tools which have been previously invented are adapted to recondition valve seats which are readily accessible. However, for many valve seats disposed in relatively inaccessible locations, such as those found in milk homogenizers, these tools are inadequate. For such valve seats special cutters have been utilized for the purpose of reforming the same. These special cutters are exceptionally expensive, are difficult to use, and shorten the life of the machine substantially. Such tools require a skilled mechanic for their proper operation in order to be assured that the valve grinding job will be done properly and that the valves will be correctly seated. In the case of homogenizers, for example, it is very important that the valves be properly seated in order to maintain the suction and discharge pressures needed to cause the machine to operate at rated capacity and to produce a product which will meet the specifications and requirements of the trade.

An object of our invention is to provide a valve seat reconditioning tool which will recondition the valve seat so as to provide it with a new but correctly inclined surface without cutting a new valve seat within the machine and thereby lengthening the useful life of the machine itself.

Another object is to provide a valve seat reconditioning tool which is capable of operation by an unskilled person without consequent injury to the machine, and with assurance of efficient results.

A more specific object of our invention is to provide a valve seat reconditioning tool which has guiding and centering means which makes it impossible for the new seat to be improperly formed.

Another object is to provide a valve seat reconditioning tool which will automatically insure that the new seat formed will have the desired angle of inclination.

A further object is to provide such a tool which obviates the use of lapping compound and its associated disadvantages and substitutes therefor an abrasive means capable of simple and ready attachment to, and detachment from, the tool.

These and other objects and advantages of our invention will more fully appear from the following description made in connection with the accompanying drawings, wherein like reference characters refer to similar parts throughout the several views and, in which:

Fig. 1 is a side elevational view of one embodiment of our invention in position for grinding the suction valve seat of a homogenizer;

2

Fig. 2 is a side elevational view of an embodiment of our invention in position for grinding the discharge valve seat of a similar homogenizer;

Fig. 3 is a vertical sectional view of the reference grinding head with its associated pilot, showing the abrasive sheet being held in position by the tapered nut;

Fig. 4 is a top plan view of the grinding head;

Fig. 5 is a vertical sectional view of the guide member;

Fig. 6 is a fragmentary side elevational view of the lower end of the revoluble driving shank with a portion broken away to show the attachment means thereof;

Fig. 7 is a side elevational view of a driving shank adapted for use with an electric driving drill in conjunction with the reference grinding head and its associated parts when grinding a suction valve seat; and

Fig. 8 is a side elevational view of a driving shank adapted for use in conjunction with an electric driving drill in conjunction with the reference grinding head and its associated parts when used to grind a discharge valve seat.

Fig. 9 is a plan view of one of the abrasive sheets used in conjunction with the grinding head.

One embodiment of our invention is shown in Fig. 1 in position for grinding the suction valve seat 10 which is formed in the block 11 of a homogenizer H. As shown in Figs. 1-8, the invention includes a reference grinding head 12 which is generally frusto-conical in shape and has, as shown, a hexagonally shaped recess 13 in its upper portion. Extending downwardly from the lower portion of the reference grinding head 12 is a cylindrical portion 14 which has external threads 15 formed thereon adjacent the grinding head 12 and which has a recess 16 in its lower end. This recess 16 is provided with threads 17 adapted to co-operate for threaded engagement with the thread of a screw bolt 18. Threaded onto the cylindrical portion 14 adjacent the head 12 is a tapered nut 19. This tapered nut 19 has its tapered sides of exactly the same inclination as the inclination of the frusto-conical periphery of the reference grinding head 12. Carried by the cylindrical portion 14 is a freely rotatable pilot member 20 which is maintained in position below the tapered nut 19 by the screw bolt 18. This pilot member 20, as shown, is cylindrical and of dimensions to fit snugly within the bores 21 and 22 of the homogenizer H. An abrasive sheet 23 is annularly arranged around the frusto-conical periphery of the grinding head 12 in flush surface relation thereto.

The grinding head 12 may have its frusto-conical periphery formed at whatever angle of inclination is desired. For example, if the angle of inclination of the valve seat to be reconditioned was originally 45 degrees, then a reference grinding head 12 having a 45 degree angle to its frusto-conical periphery should be used to recondition that particular valve seat. The reference grinding head 12 is used as a reference and the brasic sheet 22 assumes the same angle when arranged as shown in Fig. 3. The abrasive sheet 22 is formed by cutting the same from a pattern which is obtained by splitting a cone of the desired angularity and flattening the same upon a flat surface. The abrasive sheet shown in Fig. 9 is a 45 degree angle sheet.

A revoluble drive shank 23 which is adapted to have torque applied thereto is utilized to provide the necessary driving power to cause the reference grinding head 12 to turn relative to the valve seat to be reconditioned. As shown in Fig. 1 this shank 23 may be in the form of a speed wrench. The lower end of the shank 23 is provided with a recess 24, a small tension spring 25 and a small metal ball 26 arranged as shown in Fig. 6. The metal ball 26 in conjunction with the spring 25 provides a means for instant attachment or detachment of the shank 23 to the reference grinding head 12 by way of the recess 13 of the head. The lower end of the shank 23 of course must be of equal dimensions to the dimensions of the recess 13 in the upper portion of the reference grinding head 12.

A frusto-conical guide member 27 is provided for use in conjunction with the shank 23. This guide member 27 has an opening 28 extending therethrough which is of dimensions to snugly accommodate, in sliding relation thereto, the shank 23.

Fig. 7 shows a drive shank 29 which has its lower end of the necessary dimensions and shape to snugly fit within the recess 13 of the reference grinding head 12. Fig. 8 shows a similar shank 30 of shorter length. These structures are both adapted for use in conjunction with a power drive drill when reconditioning the valve seats 10 and 31.

Operation

When it is desired to recondition the suction valve seat 10 the device is arranged as shown in Fig. 1. The reference grinding head 12 must first be prepared so as to present an abrasive surface to the seat 10. To do this the tapered nut 18 is loosened slightly with the fingers and the brasic sheet 22 is annularly arranged about the frusto-conical periphery of the reference grinding head 12 in flush surrounding relation thereto. The tapered nut 18 is then tightened so as to hold the abrasive sheet 22 immovable relative to the reference grinding head 12. This is accomplished as the result of the tapered portion of the nut 18 being of exactly the same angle as the frusto-conical periphery of the reference grinding head 12. The tapered nut 18 clamps the lower edge of the abrasive sheet 22 upwardly against the grinding head 12 and holds the entire sheet 22 in flush surrounding relation since the sheet has been accurately formed to be of the exact size necessary to surround the frusto-conical periphery of the reference grinding head 12. The reference grinding head 12 is then slid through the opening shown on the right-hand side of Fig. 1 which is open because of the previous removal of the plunger port cover (not shown). The reference grind-

ing head 12 is dropped into position so that the pilot 19 fits into the bore 20 of the homogenizer H. The pilot 19 serves as a centering device and provides a bearing for the reference grinding head 12. This pilot 19 insures that the reference grinding head 12 is at all times correctly aligned relative to the valve seat 10. The shank 23 is then inserted through the opening 28 of the guide member 27 and then inserted from the top of the block 11 of the homogenizer H down into attaching position with the reference grinding head 12. The spring actuated metal ball 26 serves to retain the reference grinding head 12 thereon, and the complementary hexagonal shapes of the lower end of the shank 23 and the recess 13 co-operate to enable an operator to cause the head 12 to turn relative to the seat 10 by revolving the shank 23. While this operation is being performed the guiding member 27 which, as shown, rests within the top opening of the block 11, maintains the shank 23 and the reference grinding head 12 in true position relative to the bore 20. This insures that the seat after it has been reconditioned by repeated turning of the reference grinding head 12 and its abrasive sheet 22 will have the proper angle. This angle will be the same angle found in this seat when the machine was new. If desired, the shank 29 may be used in conjunction with an electric driving drill (not shown) instead of the shank 23. This is recommended, however, only when the valve seat 10 is extremely worn.

When it is desired to recondition the discharge valve seat 31 a similar operation is performed with the exception that the reference grinding head 12 and its associated parts, the pilot 19, the abrasive sheet 22, and the nut 18, are dropped into position from above, so that the pilot 19 will, in conjunction with the bore 21, provide the necessary centering for the reference grinding head 12 and a bearing in which it may turn. The guide member 27 is utilized in the same manner as described above. Again, a different shank such as the shank 30 may be utilized in conjunction with a power driving drill instead of the shank 23 if the seat 31 is extremely worn. The operation of reconditioning the discharge valve seat 31 is best shown in Fig. 2.

One advantage of our invention is that it provides a grinding head which can be used as a reference member upon which the abrasive may be applied which will insure the formation of a reconditioned valve seat conforming in specifications to a new valve seat in a new machine. There is no excess loss or shortening of the life of such a machine such as is experienced with the cutting devices currently in use. It is readily apparent that only a minimum of the block 11 is removed in the operation.

Another advantage is that our device may be operated by unskilled labor without danger of a new valve seat being formed which is not properly oriented relative to the bores 20 and 21. Our device is easy to use and simple to operate. It is impossible for even the most unskilled laborer to prepare a reconditioned valve seat with our device which does not accurately conform to the specifications of valve seats found in new machines.

It should be noted that the means for readily detaching the abrasive sheet 22 from the reference grinding head 12 and of attaching a new sheet eliminates loss of time that might other-

wise be involved. At the same time the use of such abrasive sheets 22 obviates the need of lapping compounds and the like and their accompanying disadvantages. The abrasive sheets 22, of course, may be of varied texture and of different shapes, depending upon the extent to which the valve seat to be reconditioned is worn and the original angle of inclination of that valve seat. The accurate reconditioning of such worn valve seats increases the efficiency of the machine in that the suction and discharge pressures needed to cause the machine to operate at rated capacity and to produce a high quality product, are maintained.

It will, of course, be understood that various changes may be made in the form, details, arrangement, and proportions of the various parts without departure from the scope of the present invention, which, generally stated, consists in the matter shown, and described, and set forth in the appended claim.

What we claim is:

A valve seat reconditioning tool comprising a frusto-conical body having an uninterrupted generally frusto-conical supporting surface and having a depending cylindrical portion, means at the upper end of said body for axially connecting said body with a revoluble driving shank, a cylindrical and rigid pilot member rotatably mounted on said lower cylindrical end portion of said body in close fitting encircling relation for free and unlimited rotation with respect thereto and extending coaxially thereof, said pilot member having an outside diameter equal to the inside diameter of the annular passage 35 inwardly of the valve seat in a block for tight

fitting engagement therewith to provide true and non-yielding centering for said frusto-conical body and constituting a bearing for said body, said frusto-conical surface supporting a flexible, arcuately shaped abrasive sheet having a pair of free ends and of a length entirely surrounding said frusto-conical surface without overlap of its ends, and a single clamping member threadedly mounted on the lower cylindrical end portion of said body between said pilot member and said frusto-conical portion for quickly and easily detachably securing the abrasive sheet in flush surrounding relation with the frusto-conical surface of said body, said clamping member being capable of releasing the abrasive sheet without itself being disconnected from said body.
